(57) **CLAIM**

The ornamental design for a valve, as shown and described.

DESCRIPTION

FIG. 1 is a view from the back showing our new design;

FIG. 2 is a view from the front of the valve shown in FIG. 1;
FIG. 3 is a view from the right side of the valve shown in FIG. 1;

FIG. 4 is a view from the left side of the valve shown in FIG. 1;

FIG. 5 is a top plan view of the valve shown in FIG. 1;

FIG. 6 is a bottom plan view of the valve shown in FIG. 1;

FIG. 7 is a perspective view from below of the valve shown in FIG. 1; and,

FIG. 8 is a perspective view from above of the valve shown in FIG. 1.

The broken line showing of unclaimed portions of the valve form no part of the claimed design.
